REINFORCING BAND FOR CONTAINERS

Chester M. MacCheaney, Chicago, and Allen B. Wilson, Evanston, Ill., assignors to Acme Steel Company, Chicago, Ill., a corporation of Illinois

Application December 31, 1934, Serial No. 759,839

2 Claims. (Cl. 229—5.7)

This invention relates to improvements in containers and reinforcing rims or bands therefor and the purpose of the invention is to provide an improved construction in which a reinforcing metallic rim is held securely in place around the top edge of the outer wall of the container, thereby protecting the top edge of the wall. The invention relates more particularly to containers of the collapsible type in which an annular collapsible non-metallic wall, formed of paper, fibre-board, or the like, is adapted to be expanded within a metallic reinforcing rim. Annular collapsible walls of this type are commonly shipped in bundles in the collapsed condition and are then unfolded and expanded at the place of use and assembled in connection with the rim and other parts of the container preparatory to filling the container with the commodity to be shipped therein. The principal object of the present invention is to provide an improved container of this type comprising an annular metallic rim which may be detachably interlocked with the top edge of the annular wall and which is adapted to protect the edge of the annular wall during the use of the container. Still another object of the invention is to provide an improved container comprising an annular collapsible wall having a series of projections adjacent its upper edge, formed preferably of metallic members which are attached thereto at intervals, in combination with an annular metallic rim having a flange adapted to interlock with said projections and having an inwardly turned flange adapted to hold said annular wall in its expanded condition, wherein the projections carried thereby interlock with the flange on the rim. Another object of the invention is to provide an improved method of forming a container according to which an annular collapsible non-metallic wall is provided adjacent its upper end with a series of metallic attaching devices forming outwardly extending projections and then placing over the end of the expanded annular wall a complete annular metallic rim having an inwardly and downwardly turned upper flange adapted to extend on the inside of the annular wall to hold said annular wall in its expanded condition wherein said projections interlock with an inwardly directed flange formed on the lower edge of said rim. Other objects relate to various details of construction and features of the improved method which will appear more fully hereinafter.

The nature of the invention will be understood from the following specification taken with the accompanying drawing, in which one embodiment

ment and two modifications of certain features of the invention are illustrated.

In the drawing:

Figure 1 is a side elevation of a typical container carrying our improved reinforcing band, a portion thereof being cut away to expose one of the attaching devices carried by the container body;

Fig. 2 is a top plan view of the container shown in Fig. 1;

Figs. 3 and 4 are sections along the lines 3—3 and 4—4 in Figs. 1 and 3, respectively, showing the relation of our improved band to the container body and the attaching devices carried thereby;

Fig. 5 is a sectional view, corresponding to that shown in Fig. 3, but illustrating a reverse positioning of the attaching devices;

Fig. 6 is a view similar to Fig. 5 but showing a modification of the attachment;

Fig. 7 is a vertical section through a container wall and another form of attachment; and

Fig. 8 is a view similar to Fig. 7 showing still another form of attachment.

Referring to the drawing, the numeral 10 designates a typical container of the collapsible type which comprises an annular cylindrical wall 11 that may be formed from paper or a similar material and which is initially cut as a sheet for subsequent bending to form the body and its overlapping end edges are secured together by glue or other fastening means. After being thus formed, these annular walls are customarily collapsed and folded flat for shipment and storage and are subsequently expanded for assembly at the point of use. The numeral 13 designates any conventional bottom for the container, while the numeral 14 indicates our improved reinforcing band or rim.

This band or rim is preferably formed from a flat metal strip 15 which is cut to an appropriate length, dependent upon the circumference of the container with which it is to be employed, and the ends thereof are secured by any conventional means, such as by spot welding. It will be understood that the band or rim may have other cross-sectional configurations than the flat formation shown, since the essential features of the invention as regards this band are directed to other aspects thereof.

The upper edge of the band 15 is curled inwardly to provide a continuous flange 15^a having a generally semi-circular section. The lower edge of the band is turned inwardly and upwardly to provide a flange 15^b adapted to inter-

lock with parts carried by the annular cylindrical wall 11.

In order to assist in retaining the band or rim 14 on the wall 11, a plurality of spaced attaching devices 16 are mounted in the wall of the annular wall 11 at a distance below the upper edge thereof determined by the width of the band. These attaching devices are preferably in the form of staples or metallic stitches and, in the form shown in Figs. 3 and 4, each staple comprises an intermediate portion 16^a, which lies in close contact with the outer surface of the container body 11, and arms 16^b which extend inwardly through the annular wall. These ends are bent towards each other or clinched to form portions 16^c, and their extremities 16^d are forced outwardly again into the body wall.

The portions 16^a of the staples provide a series of protuberances externally of the body over which the flange 15^b of the rim is hooked. In positioning the band on the container, the band is forced downwardly until the upper flange 15^a completely shields the upper edge of the annular wall 11 and with the inner edge of this flange extending downwardly for a short distance internally of the container. As the upper flange 15^a reaches this position, the lower flange 15^b is snapped over the projecting staple portions 16^a, as permitted by the resiliency of the annular wall 11, and the flange 15^b then engages the lower edges of the staple portions 16^a to secure the band in position, thus adequately stiffening the upper end of the container, and also providing a metallic reinforcement and protection for the otherwise fragile upper end of the non-metallic container wall 11. It will be observed that the curved top flange 15^a of the rim holds the annular wall 11 against inward collapse so that the staples 16 are maintained in interlocking engagement with the flange 15^b.

It is within the scope of the present invention to reverse the positions of the staples, as shown in Fig. 5, which shows a staple 17 of the same form as the staple 16 illustrated in Fig. 3, except that the body portion 17^a is located internally of the container wall 18 and the arms 17^b project through the wall and are turned inwardly or clinched to provide curved projecting portions 17^c which act in the same manner as the staple portions 16^a of the form first described.

A further modification of the staple is shown in Fig. 6, wherein the intermediate portion 18^a of the staple 19, externally of the container wall 20, is provided with a slight hump 18^b in order to increase the width of the protuberance outwardly of the container wall. The arms 18^c project through the container wall and are clinched as shown at 18^d.

It has been found in practice that the form of construction shown in Fig. 7 has many advantages because of the decreased tendency to tear the material of the annular wall under the strain of the rim which is interlocked with this form of staple or fastening device. In this construction, a staple 22 has a back wall 22^a which

is directed in a substantially vertical direction. This staple has arms 22^b and 22^c which penetrate the annular wall 23 of the container and which are inwardly turned or clinched on the inside of the container wall as shown at 22^d. The lower arm 22^c is provided with a curved or irregular portion 22^e which holds the back wall 22^a outwardly from the annular wall 23 so that the part 22^e constitutes a shoulder adapted to interlock with the lower turned flange of the metallic rim as in the forms of the construction previously described. These staples 22 are distributed at intervals around the annular wall 23.

In Fig. 8 of the drawing there is shown another modified form of construction which has the advantages of the form illustrated in Fig. 7, except that this staple or fastener is applied from the inside of the annular wall. In this modification, a staple 24 has a back wall 24^a which extends in an upright position, being united at its ends with the arm portions 24^b and 24^c which penetrate the annular non-metallic wall 25 of the container. The inner extremity of the arm 24^b is curved outwardly away from the annular wall as shown at 24^d and the extremity of the lower arm 24^c is reversely bent and clinched against the annular wall as shown at 24^e. The out-turned portion 24^d of the upper arm 24^b of the staple forms a projection which is adapted to interlock with the lower turned flange of the annular metallic rim as in the forms of the invention heretofore described.

Although certain forms of the invention have been shown and described by way of illustration, it will be understood that it may be constructed in still other embodiments coming within the scope of the appended claims.

We claim:

1. The combination of a collapsible container body having a plurality of separate circumferentially spaced metallic stitches located there-around and slightly below the upper edge thereof, and a metallic reinforcing band having an inwardly and downwardly turned flange directly engaging the upper edge of said container body to cover and protect the same and a second flange engaging the stitches, the cooperation of the flanges with the body and stitches retaining the band in position.

2. The combination with an annular non-metallic collapsible container wall having an annular series of circumferentially spaced metallic stitches forming outwardly extending projections adjacent one end of the container, of a metal rim surrounding said wall and having two annular inwardly extending flanges formed along its edges, one of said flanges being located adjacent said projections and the other flange extending on the inside of said annular wall to hold said wall expanded and thereby maintain said projections in positions wherein they interlock with said first-named flange to maintain said rim on said annular wall.

CHESTER M. MACCHESNEY.
ALLEN B. WILSON.
